Copending U.S. Appl. No. 29/775,344, filed Mar. 23, 2021, by Caldwell, et al., entitled "Bottle, Mount Assembly, and Insert Tool".
(Continued)*Primary Examiner* — Lauren R Calve*(74) Attorney, Agent, or Firm* — Merchant & Gould P.C.; Daniel R. Evans(57) **CLAIM**

The ornamental design for a bottle and a mount assembly as shown and described.

DESCRIPTION

FIG. 1 is a right, front-side perspective view of a bottle and a mount assembly.

FIG. 2 is a left, rear-side perspective view thereof.

FIG. 3 is a front-side elevation view thereof;

FIG. 4 is a rear-side elevation view thereof.

FIG. 5 is a right-side elevation view thereof.

FIG. 6 is a left-side elevation view thereof.

FIG. 7 is a top plan view thereof.

FIG. 8 is a bottom plan view thereof.

FIG. 9 is a right, front-side perspective view of a bottle and a mount assembly according to a second embodiment.

FIG. 10 is a left, rear-side perspective view thereof.

FIG. 11 is a front-side elevation view thereof;

FIG. 12 is a rear-side elevation view thereof.

FIG. 13 is a right-side elevation view thereof.

FIG. 14 is a left-side elevation view thereof.

FIG. 15 is a top plan view thereof.

FIG. 16 is a bottom plan view thereof.

The broken lines shown represent portions of the bottle and a mount assembly that form no part of the claimed design.
